UNITED STATES PATENT OFFICE.

WILLIAM E. HARKNESS, OF EAST ORANGE, NEW JERSEY, ASSIGNOR, BY MESNE ASSIGNMENTS, TO HALL SWITCH & SIGNAL COMPANY, A CORPORATION OF MAINE.

SWITCHING DEVICE

1,183,192.

Specification of Letters Patent. Patented May 16, 1916.

Application filed August 26, 1912. Serial No. 717,089.

To all whom it may concern:

Be it known that I, WILLIAM E. HARKNESS, a citizen of the United States, residing at East Orange, in the county of Essex and 5 State of New Jersey, have invented a certain new and useful Improvement in Switching Devices, of which the following is a full, clear, concise, and exact description, reference being had to the accompanying drawings, forming a part of this specification.

10 The invention herein relates to switching devices and is of more particular use in connection with a jack type test panel of particular utility in connection with the inter- 15 connecting and change of connection between various entering lines at a central station.

15 The invention herein provides novel circuit arrangements and primarily, a structure 20 in which the various interconnecting devices, such as jacks, are accessibly mounted, the structure supporting the jacks being movably mounted to permit access to the rear of the jacks without disturbing the connection. The structure is also such that the 25 wiring may be entirely open, the line terminals being connected directly to the line jacks without the use of a cable form. This greatly lessens the possibility of trouble on 30 account of lightning discharges. To further avoid lightning trouble, the ground jack used in this connection is located entirely separate from the line jacks and has a separate lead to its terminal.

35 Specifically the apparatus is such that the jacks are arranged on a panel supported in such manner that by removing two screws in the upper part of the panel, the whole panel can be swung from a vertical to a 40 horizontal position for a ready examination of the apparatus and wiring. This can be done without disturbing the line wires connected to the jacks. The frame which supports the jack panel likewise carries the terminal strips to which the line wires are 45 secured.

One embodiment of the invention will be described more specifically by referring to the accompanying drawings, in which— 50 Figure 1 is a front view of the improved jack panel; Fig. 2 is a sectional view on line b—b of Fig. 4; Fig. 3 is a view illustrating the panel portion swung about its support; Fig. 4 is a sectional view on line a—a of

55 Fig. 1; Fig. 5 shows the manner of cord

mounting; Fig. 6 is a diagrammatic circuit arrangement of the device, and Fig. 7 is a sectional view on line c—c of Fig. 1.

Referring to the drawings, the device is illustrated as comprising a back plate 1 to which the structure shown more in detail in Fig. 3 is pivotally supported. This structure comprises a jack panel 2 having at its extremities two U shaped supports 3, 3 by means of which this jack panel is mounted. 60 To mount this panel structure angle pieces 4, 4, four in number are secured to the back plate 1 and the angle supports 3, 3 are adapted to be secured to these brackets 4 by means of the screws 5. It will thus be seen that by releasing either the upper pair of screws 5, 5 or the lower pair of screws 5, 5, 65 the panel structure may be swung about its remaining supports.

On account of the entry of the line wires 70 at the lower portion of the device, the jack panel herein would probably always be swung about the lower pivots as shown in Fig. 3. Suitable connecting jacks 6, 6, sixteen in number are mounted upon this panel, 75 preferably to accommodate line wires and one jack 7 is provided for grounding purposes. The panel 2 likewise carries two switching devices 8, 8 operated by keys 9. The movable structure comprising the elements 3, 3 and the panel 2 likewise carries two strips 10, 10 mounted on opposite sides 80 of the elements 3 and secured thereto by means of the screws 11, 11. These strips 10 respectively carry the line terminals 12, 12 85 which are held in place by means of the screws 13, 13. Fig. 7 shows more in detail the scheme of open wiring for the line terminals 12 to the jacks and from one jack to another. Connecting cords of the single 90 conductor variety in this specific embodiment 14, 15, 16, 17, 18, 19, 20 and 21 respectively have their terminals suitably connected to binding posts 22 and are held in place by the customary straps 23. A ground 95 terminal 24 is likewise provided which is connected directly to the grounding jack 7. It may be said, of course, that while the system is herein shown for use in connection with single conductor cords and plugs, it is 100 likewise available for two conductor purposes and its modification to such a system will be readily apparent to those skilled in the art.

105 In order to inclose the entire structure so 110

that the parts will be free from outside interference, a casing 25 is provided having four sides 25 and a front cross piece 26, all comprising a unitary structure which is set 5 over the apparatus as shown more clearly in Figs. 1, 2 and 4 and is then held in place by means of eyelets or catches 27, 27, thus presenting a closed structure.

Referring more specifically to Fig. 6 the 10 system of wiring is set forth. It will be noted that each jack 6 has a terminal respectively connected to its associated binding post 12. The lower two jacks on either side are adapted for use to accommodate for incoming 15 grounded lines or two incoming metallic lines. The two jacks on each side directly above the two first mentioned are adapted to accommodate either two through grounded lines or one through metallic line, 20 as the lines are continuous by reason of the conducting wires 27, 27. The upper two jacks on either side are adapted to accommodate through a metallic line and the left hand switching device 8 is connected through 25 the agency of the conductors 28, 28. The terminals 29, 29 of this switching device are designed to have the train despatcher's telephone and selecting equipment attached thereto, so that the through line associated 30 with the upper pair of jacks is directly connected with the train despatcher's telephone and selecting equipment as will be readily apparent from the connections. Similarly the next two pairs of jacks on either side are 35 adapted to accommodate a second through line having telephone and despatching equipment associated therewith in bridge by means of the conductors 30 which lead to the right hand switching device 8 whose terminals 31, 31 are adapted likewise to accommodate a telephone and signaling device. Normally the train despatcher may be on the circuit accommodated by the upper pair of jacks, the left hand switching device 8 being 40 in the circuit condition illustrated. Now should this particular circuit become faulty, however, or should the train despatcher desire to connect himself with any other circuit, or should he desire, for instance, to 45 complete the incoming circuit of the two upper right hand jacks through the jack on the left side in order to get a more perfect line, then the connecting plugs are brought into use. In order to complete this last 50 named connection, plug 17 would be connected to the upper right hand jack 6 and plug 16 would be connected to the fifth left hand jack 6. Then plug 15 would be connected to the second right hand jack 6 and plug 14 would 55 be connected to the sixth left hand jack 6. The line that thus enters the upper two right hand jacks would be cut off from the upper two left hand jacks and would be completed through the fifth and sixth jacks on the left 60 side of the panel. In this condition however

the selecting and telephone equipment connected to the terminals 29, 29 would not be on this line and to restore its association with this line the button 9 is actuated so that this particular equipment is connected 70 directly in bridge of the two sets of cords as will be apparent from the illustration.

The circuit arrangement is such, as is apparent, that testing may be properly carried on by inserting a plug in any jack, as 75 the line to the left or the right is therefore cut off, and the test may be carried on on the line remaining connected to the jack. Plugs, may be used for ordinary interconnecting work without interfering with the train despatcher's equipment connected to the terminals 29, 29, as these plugs and cords are normally not connected with any line. 80

From the foregoing the advantage of thus arranging the system and structure to make 85 it accessible and of thus arranging the wiring will be readily apparent.

Modifications, may readily be made without departing from the spirit of the invention and what I therefore claim as new and 90 desire to secure by Letters Patent is:

1. In a device of the character described, the combination of a back-plate, a jack-panel, a plurality of jacks mounted thereon, a terminal member having mounted thereon 95 a plurality of terminals insulated from each other and adapted to be connected with said jacks, means rigidly connecting said jack-panel and terminal member together a predetermined distance apart and means for 100 hinging said jack-panel and terminal member to said back-plate whereby easy access may be had to said jacks and terminals by moving the same around the hinging means.

2. A device of the character described 105 having a back plate, a jack panel, a plurality of jacks mounted on said panel, supporting means mounted on said back plate, a plurality of arms extending from said panel to said supporting means, means for pivotally associating said arms with said supporting means so that when the connection between certain of said arms and said supporting means is removed, said panel may be 110 swung about the remaining supporting means, and an insulating strip carrying line terminals carried by said arms.

3. A device of the character described having a back plate, a jack panel, a plurality of jacks mounted on said panel, supporting 120 means mounted on said back plate, a plurality of arms extending from said panel to said supporting means, means for pivotally associating said arms with said supporting means so that when the connection between 125 certain of said arms and said supporting means is removed, said panel may be swung about the remaining supporting means, and a surrounding casing for said panel and jacks removably secured to said back plate. 130

4. A device of the character described having a back plate, a jack panel, a plurality of jacks mounted on said panel, supporting means mounted on said back plate, a plurality of arms extending from said panel to said supporting means, means for pivotally associating said arms with said supporting means so that when the connection between certain of said arms and said supporting means is removed, said panel may be swung about the remaining supporting means, an insulating strip carrying line terminals carried by said arms, and a surrounding casing for said panel and jacks removable secured to said back plate.

5. A device of the character described,

comprising a back plate, a jack panel pivotally associated therewith, a plurality of jacks on said panel, a plurality of plugs and cords, a key having terminals for connecting said jacks with an operator's equipment, said key being adapted to connect said equipment with said plugs and cords, whereby said equipment may then be connected with any line associated with said device.

25

In witness whereof, I hereunto subscribe my name this third day of June A. D., 1912.

WILLIAM E. HARKNESS.
